UNITED STATES PATENT OFFICE.

CLELAND DAVIS, OF THE UNITED STATES NAVY, ASSIGNOR TO ORDNANCE DEVELOPMENT COMPANY OF AMERICA, OF WILMINGTON, DELAWARE, A CORPORATION OF DELAWARE.

CONTOUR-CAP FOR ARMOR-PIERCING PROJECTILES.

1,132,453.

Specification of Letters Patent.

Patented Mar. 16, 1915.

Application filed November 11, 1914. Serial No. 871,515.

To all whom it may concern:

Be it known that I, CLELAND DAVIS, commander United States Navy, a citizen of the United States, stationed at San Diego, in 5 the county of San Diego and State of California; have invented certain new and useful Improvements in Centour-Caps for Armor-Piercing Projectiles; and I do hereby declare the following to be a full, clear, and 10 exact description of the invention, such as will enable others skilled in the art to which it appertains to make and use the same.

My present invention relates to caps for armor piercing projectiles, whereby there is 15 combined, with the projectile, a hood of such a character as to give the form or contour to the whole that is best adapted to a minimum resistance of the projectile in its flight through the air thus causing it to have a 20 greater range, a flatter trajectory, a greater danger space and a greater velocity at impact for a given range, and at the same time preserve it in a state of the greatest efficiency for the penetration of the armor. My Patent, No. 945,492, granted January 4, 1910, 25 provided for these qualities in an armor piercing projectile as has been demonstrated by the general use of the construction therein described. My present invention is an 30 improvement on that design, principally from a manufacturing point of view.

In order to give a better understanding of the nature of my invention, I will give briefly the generally-accepted theory of the 35 resistance of face hardened armor and the function of the soft steel cap now universally used on all armor piercing projectiles.

First, when a pointed projectile strikes the hard elastic face of an armor plate, there 40 occurs an elastic or diaphragmatic dishing of the hard face, which distributes the resistance over a considerable area and causes the stress of impact to react upon the projectile and tend to stop it in a distance equal 45 to the versed sine of the dished face. If the projectile is strong enough to withstand the force of impact without breaking up and, if it have sufficient velocity after the energy required to elastically dish the hard 50 plate has been expended upon it, then penetration begins to occur and the resistance of the plate becomes purely local, the amount

of penetration depending upon the remaining velocity of the projectile.

Now let us observe what happens when 55 the shell fitted with a soft steel cap surrounding and inclosing the point strikes a hard face armored plate. When the mass, consisting of the cap and shell, strikes the hard face of the armor plate, the energy of 60 impact of the whole mass is transmitted to the plate through the soft steel cap, which must be strong enough to perform this function, and there occurs the same elastic or diaphragmatic dishing, that portion of the 65 energy of impact required for the elastic dishing being concentrated as before at the point of impact, and tending to stop the impinging shell; but the work done on the projectile by the resistance offered by the 70 plate, in the elastic dishing caused by the impact, instead of being concentrated on the projectile, during the time it takes for the projectile to move through the space equal to the versed sine of the dished face, 75 is in this case distributed over a considerably greater distance, or that equal to the versed sine of the dishing, plus the distance the point of the projectile has to travel in piercing the soft steel cap, remembering 80 that the cap itself, while strong enough to transmit the stress of impact to the plate, offers little resistance to the passage through it of the hard point of the shell; obviously then the work done on the shell upon impact brings much less strain upon the shell 85 fitted with a soft steel cap than upon a shell striking without a cap, greatly decreasing the tendency of the shell to break.

Now a shell provided with a soft steel 90 cap, which facilitates its penetration in armor, is not of a form that will give the best results in its flight through the air, before the projectile can hit the target. In other words, the best form for penetrating armor 95 is not the best form for flight, and the converse of this is also true, the reasons being known to all who are familiar with the art. Now the best form for flight is a shell with a long, pointed, conical contour, and it has 100 been the effort of ordnance engineers to perfect a cap that would combine these qualities, i. e., one that would have the best form of penetration and at the same time have a

contour that would offer minimum resistance in the passage of the projectile through the air.

Many forms of caps have been tried; 5 solid caps of steel, caps made partly of steel and partly of frangible material, the latter being attached to the steel cap proper, and the idea being that the frangible material would be destroyed and dissipated and thus 10 not interfere with the functioning of the soft steel cap proper; and finally, caps in which the forward or contour portion has been hollowed or chambered out—this latter, as disclosed in my Patent No. 945,492, 15 has been the only form that has successfully combined the two qualities, (a) of the most desirable form for penetration and (b) the most desirable form for flight.

In order to lead to a better understanding 20 of my invention, which will hereinafter be explained, I will give the causes of the failure of the long pointed solid cap, both the one of solid steel and the one with the frangible point. In the case of the long 25 pointed solid cap, referring again to the theory of the resistance of face hardened armor as above given, when the mass consisting of the shell and the long pointed solid cap strikes the hard faced plate, there 30 occurs the same diaphragmatic dishing as before, the stress of impact being transmitted to the plate through the cap and the projectile continuing on its way through the cap which offers comparatively little 35 resistance to its progress, but by the time the point of the projectile has gone through the cap and reached the plate, the elastic reaction of the hard face of the plate has caused it to spring back to its original plane 40 and the effect of the preliminary blow is lost; in other words, there must be a definite distance between the point of the projectile and the extreme front end of the cap, and this distance must be such that the point 45 of the projectile after it has pierced the cap should reach the plate when the latter is at the point of maximum depression and before it has had time to react.

It will be observed that there is a very 50 delicate adjustment required of the time element; the soft cap should be of such character that it will transmit the energy of impact of the mass of the shell and cap and depress the plate to the point of its elastic 55 limit and at the same time offer small resistance to the passage of the shell through it; and also should permit the point of the shell to go through it and arrive at the plate at the very instant when the latter has 60 reached the point of maximum depression and can offer only a local resistance to the shell.

In the case where frangible material has been used to form a forward portion of the 65 cap, it has been composed of a hard and

more or less resisting substance, the theory being that on account of its brittleness it would be quickly destroyed and dissipated and leave the way clear for the steel cap proper to perform its function, but these 70 efforts also failed to give results, because the substance offered sufficient compressive resistance to hold the soft steel cap and enable the point of the projectile to pass through it so that when the latter reached 75 the plate, the effect was the same as if the projectile had no cap at all.

Now in the case of the cap, with the hollowed or chambered fore portion, which is shown in my Patent No. 945,492 aforesaid, 80 the effect is as follows:—The walls being ductile, upon impact, are mashed back upon and become in fact part of the cap itself, so that the function of the latter is not interfered with. There are, however, certain 85 difficulties connected with manufacture of these hollow caps that it is desirable to avoid, and so I propose to provide in place of the hollowed or chambered portion of the cap as disclosed in said patent, a solid portion 90 of easily compressible material of a pointed form, to give the best contour for a minimum resistance, such as soft rubber, the outer surface of which may be hardened so as to preserve its shape in flight and to 95 protect it in handling, or it may be incased in another shell of vulcanized rubber, or other form of casing, to give it the requisite shape to preserve it in handling and in flight.

My invention will be understood by reference to the accompanying drawings, in which similar parts are indicated by similar reference numerals throughout the several views.

Figure 1 is a side elevation of the shell with the improved cap attached; Fig. 2 shows a central vertical section through the soft metal cap and contour cap, with the nose of the shell shown in elevation; and 110 Fig. 3 is a similar section of a modified form of soft metal cap and contour cap constructed according to my invention.

Referring to Figs. 1 and 2, A shows the shell having the usual ogival point A'. B 115 represents the soft metal cap which is provided with an annular rib b on the forward end thereof, and to which the contour cap C is attached in any convenient way, as by screw bolts or rivets D. The core of this 120 contour cap C is preferably of soft rubber, while the outer layers c are hardened so as to supply sufficient rigidity to the cap in its flight from the chamber of the gun to the target. Instead of having the contour cap 125 formed of the same mass of rubber shown in Fig. 2, I may provide a separate contour cap C', as shown in Fig. 3, with a core C' of rubber or other suitable material. This contour cap C' may be made of hard rubber, 130

metal, or other suitable material, and may be attached to the soft metal cap B' in any convenient way, as by screwing same onto the screw threads b' provided on the nose b' of 5 the soft metal cap B'.

The action of this device is as follows:— When an armor piercing projectile, fitted with a soft steel cap to facilitate penetration and a point of easily compressible material 10 of such form as to give the best contour for flight, meets the hard face of an armor plate, the contour point is compressed upon itself; the resistance it offers not being sufficient to hold a soft steel cap and enable the 15 point of the projectile to pass through it and so reach the face of the plate before the cap itself does. The whole effect being that the compressible contour point while it performs its function to give the projectile the 20 form best suited to a sustained flight through the air does not interfere with its powers of penetration; in other words, it leaves the projectile with its soft steel cap in a condition to attack the plate with its 25 powers of penetration unimpaired.

It will be obvious that various modifications might be made in the form of the contour cap and in the mode of attaching it to the projectile which could be used without 30 departing from the spirit of my invention.

Having thus described my invention what I claim and desire to secure by Letters Patent of the United States is:—

1. The combination with a pointed armor 35 piercing projectile, of a soft metal cap secured to the nose of the projectile and surrounding and supporting the point thereof, and a solid contour cap secured to the soft metal cap and tapered to reduce the resistance of the atmosphere to the flight of the 40 projectile, the said contour cap having a core of soft yielding non-metallic material, and the said contour cap with its core being adapted to yield when the projectile strikes 45 the target without interfering with the proper operation of the projectile at the moment of impact, substantially as described.

2. The combination with a pointed armor 50 piercing projectile, of a soft metal cap secured to the nose of the projectile and surrounding and supporting the point thereof, and a solid contour cap secured to the soft metal cap and tapered to reduce the resistance of the atmosphere to the flight of the 55 projectile, the said contour cap having a core of soft rubber, and the said contour cap with its core being adapted to yield when the

projectile strikes the target without interfering with the proper operation of the projectile at the moment of impact, substantially as described. 60

3. The combination with a pointed armor piercing projectile, of a soft metal cap secured to the nose of the projectile and surrounding and supporting the point thereof, 65 and a solid contour cap secured to the soft metal cap and tapered to reduce the resistance of the atmosphere to the flight of the projectile, the said contour cap having an outer inclosing shell of sufficient rigidity to 70 retain its shape during the travel of the projectile, and a core of soft yielding non-metallic material, and the said contour cap with its core being adapted to yield when the projectile strikes the target without interfering with the proper operation of the projectile at the moment of impact, substantially as described. 75

4. The combination with a pointed armor piercing projectile, of a soft metal cap secured to the nose of the projectile and surrounding and supporting the point thereof, and a solid contour cap secured to the soft metal cap and tapered to reduce the resistance of the atmosphere to the flight of the 80 projectile, the said contour cap having an outer inclosing shell of sufficient rigidity to 85 retain its shape during the travel of the projectile, and a core of soft rubber, and the said contour cap with its core being adapted to yield when the projectile strikes the target without interfering with the proper operation of the projectile at the moment of impact, substantially as described. 90

5. The combination with a pointed armor 95 piercing projectile, of a soft metal cap secured to the nose of the projectile and surrounding and supporting the point thereof, and a solid contour cap secured to the soft metal cap and tapered to reduce the resistance of the atmosphere to the flight of the 100 projectile, the said contour cap comprising a mass of soft rubber adapted to yield when the projectile strikes the target without interfering with the proper operation of the projectile at the moment of impact, substantially as described. 105

In testimony whereof, I affix my signature, in presence of two witnesses.
